JAMES BUNYAN, OF FLUSHING, NEW YORK.

CLOTHES DRIER.

Application filed March 5, 1927. Serial No. 173,091.

This invention relates to new and useful improvements in clothes driers and its object is to suspend clothing after having been laundered, so that it may be readily dried. 5 Another object of the invention is to support articles of clothing in such a manner as to prevent colors from running during the drying process.

A feature of the present invention is its 10 adaptability to use indoors, which is accomplished by making the device foldable, so that when not in use it may be folded into a compact space and will occupy no floor area. 15 Another feature of the invention is the arrangement of parallel clothes supporting members, which are so positioned as to prevent the articles of clothing suspended on any one of the upper members from contact- 20 ing with those supported on the members of a lower plane.

It has been customary in the past to provide clothes driers of varying forms, such as those of the umbrella type, which are supported on a single standard and are ordinarily used in the open. Another type which has been used extensively is that consisting of a rigid frame, suspended on flexible members passing over pulleys secured to the 30 ceiling of a room, and which is raised or lowered by manipulation of the flexible members. Such devices have been found admirable for their intended purpose, but, owing, to the size of the exterior clothes drier, 35 that is, the umbrella type, they have proven impracticable for indoor use. Furthermore, those designed for indoor use, by reason of the natural limitations surrounding indoors clothes drying, have been found inadequate 40 to accommodate a moderate or large sized laundry, and it is, therefore, another object of the present invention to increase the drying facilities, and yet permit the device to be folded into small compass and 45 well out of the way when not in use.

With the above and other objects in view, the invention consists in the novel construction, combination, and arrangement of parts, which will be fully set forth in the following specification, claimed, and illustrated in the accompanying drawing in which:—

Figure 1 is a perspective view of a clothes drier, constructed in accordance with this invention, showing the same extended and 55 ready to receive the articles of clothing,

Figure 2 is a side view of the drier in folded position, and,

Figure 3 is an end view of the drier.

Referring to the drawings in detail, a pair of frames 10 comprising side bars 11 and 12 are arranged in spaced parallel relation and connected at their ends to a top bar 13 and a bottom bar 14. Extending vertical between the side bars 11 and 12 of each frame is a reinforcing bar 15, which is intersected intermediate its ends by a horizontal bar 15'. The drier as a unit, consists of a pair of such frames which are connected by flexible members, such as ropes 16, threaded back and forth through openings 17 formed in the bottom bar 14 in staggered relation to openings 18 formed in the horizontal bar 15' of each frame.

The drier above described, is suspended from the ceiling of a room, preferably in the cellar or attic by means of hinges 19 which may be fastened directly to the joists or to a plate secured to the joists in such a manner that the openings in opposite frames align.

In order to suspend the device in extended position, suitable hooks 20 are secured near opposite ends of the drier in such a manner as to engage eyes 21 carried by the frames and hold said frames from swinging movement.

In use, the drier is extended as illustrated in Figure 1, and the clothing to be dried is then hung on the parallel runs of the rope 16. Obviously, owing to the staggered arrangement of the openings in the bar 15' with relation to those in the bottom bar 14, the clothing suspended on the upper runs of the rope will be held out of contact with that suspended on the lower runs. In this manner, a thorough drying of all of the clothing is assured, and danger of color running from one article of clothing to another through mutual contact is avoided.

When the drier is not in use, it may be folded up against the ceiling, as shown in Figure 2 and held in such position by hooks 22 which engage in eyes 23. Obviously, in this position the entire floor space is free and unobstructed and the device is retained entirely out of the way but ready for instant use.

While in the foregoing there has been shown and described the preferred embodiment of this invention, it is to be understood

that minor changes in the details and construction, combination and arrangement of parts, may be resorted to without departing from the spirit and scope of the invention as claimed.

What is claimed is:—

A clothes drier comprising a pair of frames, normally disposed in a vertical position and hinged in spaced relation to a rigid support, the bottom bar of each frame being provided with openings, a horizontal bar carried by each frame in spaced relation to the bottom bar thereof, said horizontal bar being provided with openings in staggered

relation to the openings in the bottom bar, ¹⁵ flexible members extending through the openings in the bottom bars, and flexible members extending through the openings in the horizontal bars, whereby articles of clothing suspended on the second mentioned ²⁰ flexible members will avoid contact with articles of clothing suspended on the first mentioned flexible members.

In testimony that I claim the foregoing as my invention, I have signed my name ²⁵ hereto.

JAMES BUNYAN.
